UNITED STATES PATENT OFFICE.

ARCHIBALD J. TURNER, OF CHICAGO, ILLINOIS, ASSIGNOR TO WILSON-WESTERN SPORTING GOODS COMPANY, OF CHICAGO, ILLINOIS, A CORPORATION OF DELAWARE.

INFLATABLE BALL.

Application filed May 29, 1926. Serial No. 112,428.

My invention relates to inflatable balls, and is concerned with the provision of improvements pertaining to the bladder insertion openings of such balls.

5 In certain types of inflatable balls, notably basketballs, it is quite essential that there be nothing on the cover, projecting beyond its normal spherical surface, which will interfere with the bound of the ball or 10 reliable to become caught in a basket frame or the like. Outside or exposed lacings as heretofore used on basketballs have materially affected the bound of such balls and frequently have become caught in basket 15 frames and the like. Moreover, such exposed lacings as heretofore used have become worn by contact with the floor and other surfaces engaged by the ball in play. Because of these considerations it has become customary to provide basketballs with 20 interior or concealed lacings (of which a preferred commercial type is illustrated in my co-pending application, Serial No. 24,337, filed April 20, 1925).

25 Notwithstanding the practicability of the interior or concealed style of lacing now commonly used in connection with basketballs, there has continued to be and is a demand for a basketball provided with visible and 30 readily accessible lacing. The purpose of the present invention is to provide a visible and readily accessible lacing, which is not subject to the objections applicable to outside or exposed lacing, as heretofore employed.

While the improvements of the present invention are primarily intended to be applied to basketballs and other inflatable balls, it is contemplated that the advantages of the 40 present invention may in a measure be realized in balls which are stuffed or which have their covers filled out by some means other than an inflated bladder.

In the accompanying drawing

45 Figure 1 is an elevational view of the basketball embodying the improvements of the present invention,

Figure 2 is an enlarged fragmentary plan view of those portions of the ball with which the present invention is particularly concerned,

50 Figure 3 is an enlarged fragmentary plan view of the interior of those portions of the

ball with which the present invention is particularly concerned,

55

Figure 4 is a fragmentary sectional view taken on the line 4—4 of Figure 2, and

Figure 5 is a fragmentary sectional view taken on the line 5—5 of Figure 3.

Similar characters of reference refer to 60 similar parts throughout the several views.

In the drawing I have illustrated a basketball comprising the usual cover consisting of the several leather members 10—10 which are stitched together in the conventional or 65 any suitable manner. Adjacent portions of a contiguous pair of the cover members 10—10 are cut away as indicated at 11—11 to provide a bladder insertion opening of substantial dimensions. Although the particular dimensions of this insertion opening 70 are not essential, I will say that in a basketball of standard size this insertion opening is preferably one (1) inch wide by four (4) or five (5) inches long.

75

Stitched to the interior surface of the cover members which are cut away, as aforesaid, are closure flaps 12—12, which are formed of a good quality of flexible leather. In commercial practice it is sometimes desirable to form these flaps 12 of two-ply leather, but for the purpose of clearness in illustration they are shown in the accompanying drawing as being formed of one-ply leather. These closure flaps have 80 straight proximal edges indicated at 13—13, which were adapted to abut along the medial longitudinal line of the insertion opening aforesaid. These closure flaps are secured to their associated cover members 10—10 by 85 the several lines of stitching 14, 15 and 16, and also by the welt stitches 17 which secure the said cover members together.

Formed in the closure flaps 12—12 are two 90 rows of apertures, each of these apertures 95 preferably being paired with an aperture of the other row and being located directly opposite the same with reference to the contacting proximal edges of the said closure flaps.

100 Passing through the said closure flap apertures and comprising portions overlapping the abutting margins of the closure flap, on both the interior and exterior surfaces of said cover flaps, is a lace, generally 105 indicated at 18, which when properly ap-

plied serves to hold the proximal edges of the closure flaps in abutting relation to close the bladder insertion opening.

While the specific manner of threading the lace through the several closure flap apertures is not material so far as the present invention is concerned, I will say that I prefer to employ the style of lacing which is fully described in my co-pending application, Serial No. 112,427 filed May 29, 1926, Patent No. 1,621,043, that is a style of lacing which affords a plurality of parallel two-ply exterior lace portions, indicated in the drawing at 19, and a plurality of crossing one-ply interior lace portions indicated in the drawing at 20 which maintain the parallelism of the external two-ply lace portions aforesaid.

Regardless of the style of lacing employed, it is desirable that the exposed portions of the lace, whether they be one-ply or two-ply, shall be of substantially the same thickness as the cover members 10—10. In order that the ball when landing with the lace engaging the playing floor will have substantially the same bound as is given the ball when any other part of its exterior surface engages the playing floor, it is, of course, desirable that the exposed portions of the lace, whether one-ply or two-ply, be not substantially thicker than the cover members 10—10.

The lace employed is preferably either a good quality flat fabric lace or a thong formed of calf skin or buck skin, which is thin, strong and tough. When a fabric lace is employed its ends are preferably knotted together, as indicated at 21, the knot being slipped back between the proximal edges of the closure flaps in order that it may not be visible.

It will be understood that the ball cover here illustrated may, if desired, be provided with the conventional fabric lining (not shown). Furthermore, and if desired, the cover may be provided with a leather flap 22 which will lie between the interior portions of the lace and the bladder to prevent chafing of the bladder. When the said protecting flap is employed, it is preferably held in position by a line of stitching indicated at 23.

I have not illustrated a bladder in the ac-

companying drawing because the present invention is not concerned with any of the details of a bladder. The improvements of the present invention may be applied to a ball of the type wherein a bladder is inflated after the closure of the insertion opening, or may be applied to a ball equipped with the old style bladder provided with a rubber inflation tube which must be closed and tucked back inside the cover after inflation of the bladder has been effected.

Having thus illustrated and described a preferred embodiment of my invention, what I claim is new and desire to secure by Letters Patent of the United States is—

1. An inflatable ball comprising a cover having portions thereof cut away to afford an insertion opening of substantial length and width, closure flaps secured to the interior surface of the cover and provided with proximal margins adapted to meet in the medial longitudinal line of the insertion opening, apertures in the said closure flaps, and a lace extending through said apertures to secure the proximal margins of the closure flaps together, the exposed portions of the lace lying wholly within the boundaries of the insertion opening aforesaid.

2. A ball provided with a leather cover having a depression of substantial length and width formed in the outer surface thereof, a slit formed in said cover along the medial longitudinal line of said depression, and a lace, having its exposed portions lying within said depression, closing said slit.

3. A ball comprising a protecting casing having an elongated relatively wide slot therein, reinforcing strips secured to the inner face of the casing on opposite sides of the slot and meeting at the longitudinal center thereof defining an entrance slit, said reinforcing strips lying inward of the outer surface of the casing defining a countersunk portion, each of the strips being provided with a row of openings, and a lacing threaded through the opening against said reinforcing strips and lying in said countersunk portion, as and for the purpose specified.

In witness whereof, I hereunto subscribe my name this 27th day of May, 1926.

ARCHIBALD J. TURNER.
